UNITED STATES PATENT OFFICE.

JESSE V. ZIMMERMAN, OF LITTLE ROCK, ARKANSAS.

WATCH AND CLOCK OILER.

SPECIFICATION forming part of Letters Patent No. 349,677, dated September 21, 1886.

Application filed July 13, 1886. Serial No. 207,859. (No model.)

To all whom it may concern:

Be it known that I, JESSE V. ZIMMERMAN, a citizen of the United States, residing at Little Rock, in the county of Pulaski and State 5 of Arkansas, have invented certain new and useful Improvements in Watch and Clock Oilers, of which the following, taken in connection with the accompanying drawings, is a specification.

10 My invention is designed more particularly for application to the bottles in which the ordinary watch and clock oil of commerce is supplied to the market, (although it may be applied to a can or other vessel,) and has for 15 its object to produce an oiler which shall be simple and inexpensive in construction, and shall protect the oil from dust and wastage, and shall be adapted to the oiling of both watches and clocks, as may be desired.

20 To this end the invention consists in the peculiarities of construction and combinations of parts, as hereinafter described, whereby the flow of oil from the bottle or receptacle is regulated, and the size of the discharge-orifice in 25 the end of the nozzle enlarged or diminished at pleasure, to adapt it to the lubrication of bearings of different sizes.

Referring to the drawings for a better understanding of my invention, Figure 1 is a sectional elevation of a bottle with my improved devices applied thereto. Fig. 2 is a modification of the same, in which such devices are shown applied to an ordinary can; and Fig. 3 is a sectional detail upon an enlarged scale, 35 showing more clearly certain features of my invention.

A represents a bottle or other convenient receptacle in which oil is to be contained, and B is the stopper therefor. This stopper, to 40 which my improvements are applied, may be made of any suitable material, but preferably of cork, and has passing through its center longitudinally of its axis the tube or nozzle C, which, being somewhat greater in length than 45 said cork, extends both above and below the same. D is a needle or rod arranged within said tube or nozzle so as to project a short distance beyond the ends thereof, and is provided at a suitable point near its lower end 50 with a collar, d, and an elastic washer, e, the two latter forming a valve by means of which

the flow of oil from the bottle or receptacle is controlled.

E is a spiral spring connected at one end to the stopper and at the other to the lower end of the needle or rod, and serves to hold the latter normally thrust forward with its upper end protruding from the upper end of the tube or nozzle, and to press the collar and elastic washer thereon against the lower end of the same.

F is a cap detachably secured to the upper end of the tube or nozzle, and is provided in its upper end with a discharge-orifice of smaller diameter than that of the interior of 65 the tube or nozzle, its object being to adapt the oiler to the lubrication of bearings of smaller dimensions than is practicable when the said tube or nozzle alone is employed.

G is a vent-tube passing down through the 70 stopper to admit air to the bottle, and is provided with a suitable cap or stopper, H, as shown, to close the same when desired.

The operation of my oiler is as follows: When it is desired to oil the bearings of a 75 watch, the parts are arranged as shown in the drawings, with the cap F applied to the upper end of the tube or nozzle, so as to reduce the size of the discharge end thereof to its lowest limit, the collar d and washer e being pressed 80 tightly against the lower end of the tube or nozzle, so as to close the same, and the needle or rod D being thrust forward, with its upper pointed end protruding slightly from the upper end of the tube or nozzle. The bottle or 85 other receptacle is then inverted, and the end of the needle or rod D is placed upon the bearing to be lubricated and gently pressed against the same. This forces the needle or rod upward within the bottle, removing the collar d 90 and washer e from the lower end of the tube or nozzle, and allowing the oil to flow through it along the needle or rod and upon the part desired. When the proper amount of oil has been supplied, the pressure is withdrawn and 95 the needle or rod returns to its original position, carrying the collar d and washer e against the lower end of the tube or nozzle, and closing it against the passage of further oil. To lubricate the bearings of a clock the parts are 100 arranged in the same manner, with the exception that the cap G is removed from the end

of the tube or nozzle, in order that the oil may flow with greater freedom, and the oiler is operated in precisely the same way as when lubricating the parts of a watch.

5 In Fig. 2 I have shown my improved oiler applied to an ordinary can, the stopper being made of such form as to screw into and fit the threaded neck thereof. In all other respects the construction shown in this figure is identical with that illustrated in Fig. 1.

I sometimes find it convenient to cover the stopper with a rubber or other cap, especially when made of cork, to exclude the air therefrom and to prevent the oil which passes through it from running down the outside of the bottle, and such an arrangement I have shown at I in Fig. 1, wherein said cap is illustrated as extending over the stopper and being secured to the neck of the bottle.

10 From the foregoing it will be seen that I produce an oiler adapted to the lubrication of watches, clocks, and other light machinery, which is exceedingly simple in construction and efficient in its operation.

15 I am aware that it is not new to construct oil-cans with needles or rods arranged within their nozzles for regulating the action of valves at their lower ends or within the same, and do not, therefore, broadly claim such combination of parts; but

What I do claim, and desire to secure by Letters Patent, is—

20 1. The combination, with the stopper B, tube or nozzle C, needle or rod D, oil-regulating valve, and spring E, secured to the stopper and 35 to the needle or rod, of the detachable cap F, applied to the end of such tube or nozzle, substantially as described.

2. The combination, with the stopper B, tube or nozzle C, needle or rod D, having the 40 collar d and elastic washer e thereon, and the spring E, of the detachable cap F; as and for the purpose set forth.

25 3. The combination, with the stopper B, having the vent-tube G and stopper H, the 45 tube or nozzle C, needle or rod D, provided with the collar d and elastic washer e thereon, and the spring E, of the detachable cap F, as and for the purposes set forth.

4. The combination, with the stopper B, 50 tube or nozzle C, needle or rod D, oil-regulating valve, spring E, and means for reducing the size of the orifice in the delivery end of said tube or nozzle, substantially as described.

JESSE V. ZIMMERMAN.
